US00D880593S

(12) **United States Design Patent** (10) **Patent No.:** **US D880,593 S**
Lee et al. (45) **Date of Patent:** **** Apr. 7, 2020**

(54) DIGITAL SIGNAGE	D417,468 S * 12/1999 Van Genechten	D20/10
(71) Applicant: LG ELECTRONICS INC. , Seoul (KR)	D483,575 S * 12/2003 Chan	D6/310
(72) Inventors: Yoonkyeong Lee , Seoul (KR); Yongho Lee , Seoul (KR); Jaewon Lim , Seoul (KR)	D509,543 S * 9/2005 Hillstrom	D20/41
(73) Assignee: LG ELECTRONICS INC. , Seoul (KR)	D524,555 S * 7/2006 Mohundro	D6/300
(**) Term: 15 Years	D613,074 S * 4/2010 Dathe	D6/300
(21) Appl. No.: 35/505,958	D662,329 S * 6/2012 Arko	D6/332
(22) Filed: Apr. 27, 2018	D677,474 S * 3/2013 Harris	D6/310
(80) Hague Agreement Data	D708,459 S * 7/2014 Heirakuji	D6/675
Int. Filing Date: Apr. 27, 2018	D723,026 S * 2/2015 Birgeoglu	D14/307
Int. Reg. No.: DM/100971	D790,232 S * 6/2017 Santos	D6/300
Int. Reg. Date: Apr. 27, 2018	D790,457 S * 6/2017 Vargas	D13/108
Int. Reg. Pub. Date: Nov. 2, 2018	D816,627 S * 5/2018 Kim	D14/126
(30) Foreign Application Priority Data	D852,274 S * 6/2019 Lim	D20/39
